UNITED STATES PATENT OFFICE.

HENRY SHAPIRO, OF PHILADELPHIA, PENNSYLVANIA.

LIGHTER.

Application filed July 25, 1927. Serial No. 208,165.

My invention relates to lighters in which a saturated wick is ignited by frictionally produced sparks.

The principal object of my invention is to provide a lighter in which the wick tube and sparking mechanism are so disposed that positiveness of operation is assured.

Another object of my invention is to provide a lighter which is so designed that it may be manufactured in compact form so as to occupy but little space in the pocket of the user, and which readily lends itself to being made from ornamental and precious materials.

Still another object of my invention is to so design the working parts that it is easily operated and the flame produced by the spark so disposed that it is readily accessible for lighting a cigar or pipe, or for other purposes.

These objects, and other advantageous ends which will appear hereinafter, I attain in the following manner, reference being had to the accompanying drawings in which

Figure 1 is a top plan view of a lighter embodying my invention,

Figure 2 a side elevation of same, and

Figure 3 a longitudinal sectional view taken substantially on line 3—3 on Figure 1.

Figure 4 is a transverse sectional view, taken on line 4—4 on Figure 3,

Figure 5 a transverse sectional view, taken on line 5—5 on Figure 3, and

Figure 6 a longitudinal sectional view, as indicated by line 6—6 on Figure 1, showing a different form of construction.

Referring now more in detail to the drawings, in which an embodiment of my invention has been shown for illustrative purposes only, the device has been shown as being provided with a case or tank 10 for containing only, the device has been shown as being provided with a case or tank 10 for containing combustible liquid 11 in which a portion of a wick 12 is immersed. It is customary in lighters of this character to fill the interior of tank 10 with cotton or other absorbent material in order to prevent liquid 11 from splashing around, but this absorbent material has been omitted from the drawings for the sake of simplicity. Liquid 11 may be introduced into tank 10 in any suitable manner but I have shown the tank provided with an opening in its bottom, through which the liquid may be introduced, which is closed by a cap 13.

A wick tube 14 communicates with the interior of tank 10 and is secured to the top of the tank in any suitable manner, as by being brazed thereto. A bar 15 is rigidly secured

to the top of wick tube 14 and provided with a channel 16 which communicates with wick tube 14 and whose upper end is enlarged to form a bowl 17 for containing the ignitable end of the wick. The end of bar 15 containing bowl 17 is reduced in diameter in order to provide an annular shoulder 18, against which a gasket 19 may be placed for sealing bowl 17 and thus preventing evaporation of the liquid in wick 12. Channel 16 may extend vertically upward from wick tube 14, terminating in a centrally disposed bowl, and bar 15 may be either provided with a shoulder placed at an acute angle to the axis of bar 15, instead of at right angles to same, or the shoulder may be omitted and a sealing action effected by a slight tapering of the adjacent surfaces.

A bore 20 extends the greater part of the length of bar 15 and is closed by a cap 21 threaded into its open end. Cap 21 is preferably recessed to receive the end of a compression spring 22 which extends into bore 20 and has its inner end secured to a pin 23 extending through slots 24, formed in either side of bar 15, and having its ends rigidly secured in the sides of a sleeve 25 which has a sliding fit on the outside of bar 15.

Cap 21, which is preferably milled on its periphery and disposed nearly flush with one end of tank 10, is adapted to be abutted by one end of sleeve 25 while the other end of sleeve 25 is disposed approximately flush with the opposite end of the tank when the sleeve is in closed position, as shown in the drawings.

Cap 21 and sleeve 25 are of the same diameter and the left hand end of the sleeve is preferably milled to resemble cap 21. Spring 22 tends to move sleeve 25 longitudinally of bar 15 so that the end of the sleeve will extend substantially beyond the end of the tank, at which time, an opening 26 in sleeve 25 is disposed above bowl 17 so that the end of wick 12 may be ignited, as will hereinafter be described. The under side of sleeve 25 is provided with a slot 27, one end of which is adapted to nearly abut one side of wick tube 14 when the sleeve is in closed position and the other end adapted to abut the opposite side of wick tube 14 when sleeve 25 is extended by the action of spring 22.

As shown in the drawings, sleeve 25 is bored for the greater part of its length to provide a sliding fit on the outside of bar 15 and is counter-bored to provide a recess, which loosely fits over the end of bar 15 con-

aining bowl 17, and to provide a shoulder 28 adapted to engage shoulder 18, or to engage gasket 19 when such gasket is employed.

When the lighter is not in use, sleeve 25 is moved along bar 15 against the action of spring 22 until shoulder 28 engages gasket 19 and the sleeve is held in this position by a latch 29, slidably mounted in a tube 30 inserted in casing 10, engaging a notch 31 formed in the under side of the sleeve; the latch being moved upwardly by the action of a spring 32 mounted in the bottom end of tube 30. Latch 29 may be depressed against the action of spring 32 by means of a button 33 whose head rides on the end of casing 10 and whose stem is fixed in the latch and slideable in the end of a recess 34 formed in the top of casing 10 by depressing a small portion immediately above tube 30 to provide clearance for the bent end of latch 29 when same is depressed. The upper end of latch 29 is provided with a beveled face which is adapted to be engaged by the end of sleeve 25 for depressing the latch in the customary manner.

A post 35 is suitably secured to the top of casing 10 near its center in any suitable manner, as by riveting or brazing, and has a flint tube 36 rigidly secured in its upper end. This tube has one end threaded to accommodate a screw 37 and its other end shaped to form a housing 38 in which one end of a shaft 39 is journaled; the other end of which is journaled in a bearing 40 secured to the top of tank 10.

A gear wheel 41 is rigidly secured to shaft 39 and adapted to mesh with rack teeth 42 stamped in or formed on the side of sleeve 25. In this model of lighter, either gear teeth may be employed or the periphery of gear wheel 41 merely roughened or notched so as to engage an uneven surface or notches formed on the side of sleeve 25. A flint wheel 43, having a roughened periphery, is fixed to shaft 39 in close proximity to gear wheel 41 and is engaged by a piece of flint, or other spark producing material, 44 contained in the end of flint tube 36 and held into engagement with flint wheel 43 by a coiled spring 45, the tension of which is regulated by screw 37. Housing 38 is provided with a downstanding flange 46 which extends around substantially three-fourths the periphery of flint wheel 43 in order to cover same but is omitted between flint tube 36 and bowl 17 in order to expose wick 12 to the sparks produced by wheel 43 and flint 44.

Assuming that the lighter parts are in the positions shown in the drawings and it is desired to light wick 12, button 33 may be moved downwardly so that latch 29 is withdrawn from notch 31 and spring 22 allowed to thrust sleeve 25 longitudinally of bar 15 and cause rotation of gear wheel 41, due to its being in mesh with rack teeth 42 on the side of

sleeve 25, and cause opening 26 to align with bowl 17 and expose the top of wick 12. As flint wheel 43 and gear wheel 41 are both fixed to shaft 39, flint wheel 43 will be rotated and abrade the end of flint 44, causing the production of sparks which will be hurled against the top of wick 12 and ignite same. When it is desired to extinguish the flame on wick 12, sleeve 25 is moved along bar 15, against the action of spring 22, until shoulder 28 engages gasket 19, thus extinguishing the flame and seating bowl 17 so that the liquid in wick 12 will not evaporate. As the end of sleeve 25 approaches cap 21, it will engage the beveled face of latch 29 and cause same to be depressed. As shoulder 28 meets gasket 19, latch 29 will spring into notch 31, and lock sleeve 25 in this position.

Referring now to Figure 6, the modification shown is similar in all respects to the embodiment shown in the other views with the exception of the means of rotating the flint wheel. In this instance, a tube 47 is inserted through the top of casing 10* and provided with a bearing 48 in its lower end in which one end of a shaft 39* is rotatably mounted; the upper end of this shaft being journaled in housing 38 and carrying a gear wheel 41 and a flint wheel 43, as previously described. A coiled spring 49 encircles shaft 39* and has one of its ends secured to tube 47 and its other end secured to shaft 39* in any suitable manner, as by being inserted through a hole 50 drilled through the shaft. Shaft 39* is rotated until spring 49 is under sufficient tension before gear wheel 41 is brought into engagement with rack teeth 42 on sleeve 25 so that, when sleeve 25 is released from latch 29, spring 49 may simultaneously drive sleeve 25 along bar 15 and rotate flint wheel 44 so as to produce sparks for lighting wick 12. In this instance, I find it advisable to form well defined teeth on gear wheel 41 and on sleeve 25 in order that there may be no slippage between the gear wheel and the sleeve.

In the modification shown in Figure 6, bar 15 need not be bored for accommodating spring 22 although both springs 22 and 49 may be employed if so desired. If a hand operated lighter is desired, springs 22 and 49, tube 47, and bore 20 may be omitted and wheel 41 operated by the thumb of the user, thus producing a very inexpensive lighter.

While I have illustrated and described certain embodiments of my invention, it will be readily understood that other modifications may be made without departing from the spirit thereof, and hence I do not limit myself to the precise construction set forth, but consider that I am at liberty to make such changes and alterations as fairly come within the scope of the appended claims.

I claim:—

1. A lighter including a casing, a telescop- 130

ing wick container on the casing, a wick disposed therein and extending into the casing, a sparking mechanism engaging the wick container, and means for extending the telescoping wick container.

2. A lighter including a casing, a telescoping wick container on the casing, a wick disposed therein and extending into the casing, sealing means on the wick container for sealing the wick therein, a sparking mechanism engaging the wick container, and means for extending the telescoping wick container.

3. A lighter including a casing, a wick holder on the casing, a wick in the wick holder, a reciprocable member enclosing the wick holder and provided with an opening, sparking mechanism engaging the reciprocable member, and means for reciprocating said member whereby the sparking mechanism will be operated and the wick exposed in said opening.

4. A lighter including a casing, a wick holder on the casing, a wick in the wick holder, a reciprocable member enclosing the wick holder and provided with an opening, means on said member and means on the wick holder coacting with one another for sealing the wick holder, sparking mechanism engaging the reciprocable member, and means for reciprocating said member whereby the sparking mechanism will be operated and the wick exposed in said opening.

5. A lighter including a casing, a wick holder on the casing, a wick extending into the wick holder, a sleeve having an opening therein slideable on the wick holder, sparking mechanism engaging the sleeve, and a spring adapted to slide the sleeve on the wick holder whereby the wick will be exposed in the opening and the sparking mechanism operated.

6. A lighter including a casing, a wick holder, a sleeve slideable on the wick holder and having an opening and a slot, a wick tube

securing the wick holder to the casing and 45 extending through the slot, a wick in the wick holder, sparking mechanism operatively connected to the sleeve, and means for sliding the sleeve on the wick holder whereby the wick will be exposed in the opening and the 50 sparking mechanism operated.

7. A lighter including a casing, a wick holder, a sleeve slideable on the wick holder and having an opening and a slot, a wick tube 55 securing the wick holder to the casing and extending through the slot, a wick in the wick holder, means for sealing the wick in the wick holder, sparking mechanism operatively connected to the sleeve, and means for sliding the sleeve on the wick holder whereby 60 the wick will be exposed in the opening and the sparking mechanism operated.

8. A lighter including a casing, a wick holder, a sleeve slideable on the wick holder and having an opening and a slot, a wick 65 tube securing the wick holder to the casing and extending through the slot, a wick in the wick holder, sparking mechanism operatively connected to the sleeve, and a spring in the wick holder for sliding the sleeve on the wick 70 holder whereby the wick will be exposed in the opening and the sparking mechanism operated.

9. A lighter including a casing, a wick holder on the casing, a wick therein, a sleeve 75 slideable on the wick holder and having an opening, a rotatable wheel engaging the sleeve, a sparking wheel rigidly connected to the rotatable wheel, a piece of sparking material frictionally engaging the sparking wheel, and means for sliding the sleeve and rotating the rotatable wheel whereby the wick will be exposed in the opening and sparks 80 directed thereon by the sparking wheel.

In testimony whereof I have signed my name to this specification.

HENRY SHAPIRO.
